[57] CLAIM

The ornamental design for a bed sheet set, as shown and described.

DESCRIPTION

FIG. 1 is an exploded top, side and end perspective view of a bed sheet set showing my new design; FIG. 2 is a side elevational view thereof, the opposite side being a mirror image of that shown and with a portion of the top sheet being shown broken-away for clarity of illustration;

FIG. 3 is an end elevational view thereof;

FIG. 4 is an opposite end elevational view thereof; and FIG. 5 is an enlarged perspective view of a portion of the attachment element thereof, with the remainder omitted for clarity of illustration.

Fig. 2***Fig. 5******Fig. 3******Fig. 4***
